FLUID HEATER FOR OIL WELL TREATING APPARATUS

Andrew Craig Russell, Shawnee, Okla.

Application April 24, 1950, Serial No. 157,649

1 Claim. (Cl. 257—64)

1

This invention relates to apparatus for use in the heating and treating of viscous liquids which are used in conditioning oil wells, to the end that the pumping efficiency of the well is increased. The primary object of this invention is to provide a relatively simple, inexpensive and easily-operated device capable of applying steam to oil, admixing it therewith, and reheating the mixture whereby a hot material is made available for use as desired.

The most important object of this invention is to provide improved apparatus capable of treating fluids by the application of heat through steam pressure.

This is a continuation-in-part of my co-pending application Serial No. 100,280, filed June 20, 1949, for "Oil Well Treating Apparatus"; and an important object is to provide an apparatus having a tank with tube coils disposed therein, oil passing through said coils and being heated by steam contained within the tank and surrounding the coils.

A further object of this invention is to provide a mixing chamber for the steam and oil having an elongated, tortuous path which will promote uniform heating and complete mixing of the fluids before they leave the apparatus.

An important object of this invention is to provide flexibility in operation of the heater by the special piping and control arrangement which will make possible alternate paths for the fluid to be heated, such paths being through the coils or through the tank external of the coils as required by the particular characteristics of the fluid to be heated.

A still further object of this invention is to provide heating means for petroleum products, utilizing steam as a part of the means, applied directly to the product under pressure, whereby to inhibit reactions tending to retard free flow thereof within the treating apparatus.

Other more minor objects will be made clear or become apparent as the following specification progresses, reference being had to the accompanying drawing, wherein:

The single figure is a vertical, substantially central, cross-sectional view taken through the "Fluid Heater for Oil Well Treating Apparatus" made according to the present invention.

A tank broadly designated by the numeral 10

2

is preferably circular in cross section and pressure-tight. A coil 12 of tube stock and consisting of a plurality of lengths rebent upon themselves is suitably mounted within the tank 10. An inlet line 14 connected to a pressurized oil supply (not shown) and having a shut-off valve 16 therein passes through tank 10 adjacent the top thereof and is joined to one end of the coil 12 within the interior of tank 10. A hot oil outlet line 18 passes through the bottom of tank 10 and is connected to the opposite end of coil 12 for conducting the heated fluid to equipment adapted to direct the same into an oil well to be treated.

15 A shut-off valve 20 is disposed in the line exteriorly of the tank 10. A steam supply connection 22 leading from a suitable supply of steam under pressure, external of tank 10, enters tank 10 and is joined to coil 12, bringing the steam supply into communication with the oil contained therein. A shut-off valve 24 in steam connection 22 controls the flow of steam into coil 12.

25 A plurality of steam supply lines 26 are connected to and open directly into tank 10, whereby steam is introduced into the space surrounding coil 12. Valves 28 control the flow of steam into tank 10 through steam lines 26. Uniform distribution of heat is insured by the use of the multiple inlets. A steam outlet line 30 connects the uppermost end of tank 10 with the steam supply to provide for circulation of the steam and the early removal of air which might become trapped in the tank 10 and exclude introduction 30 of the steam thereinto. The valve 32 operably closes line 30 when required by the operation of the heater.

35 A safety valve 34 connecting the interior of tank 10 with the atmosphere is adjustable to open and vent the tank 10 to the atmosphere when the pressure therein exceeds a predetermined, safe working maximum. When the pressure returns to normal, valve 34 closes and confines the fluid to the space within tank 10. A steam trap 40 subjacent to tank 10 is connected thereto by conduit 38 which communicates with the bottom of tank 10 and has a valve 40 therein to isolate the steam trap 36 from tank 10 as required.

45 Trap 36 insures that any accumulation of steam condensate in the bottom of tank 10 will

be drained off, thereby maintaining the tube coils 12 completely surrounded by steam at all times. An interconnecting line 42 is joined to oil inlet 14 and enters tank 10. A shut-off valve 44 in line 42 allows the selection of this flow path as required by the operation of the system.

A second interconnecting line 46 is disposed between coil outlet line 18 and tank outlet line 38, thereby placing coil 12 in communication with trap 36, when required by the introduction of steam in coil 12 and as selected by opening shut-off valve 48. A third interconnecting line 50 is joined to oil outlet line 18, and the bottom of tank 10. A valve 52 controls the flow of the contents of tank 10 into line 18.

In operation, oil to be processed is supplied to the heater through line 14 from an oil storage, the contents of line 14 being pressurized and circulated by a suitable pump. Said storage and pump not being a part of this invention are not shown in the drawing. With valves 16 and 24 open, oil enters coil 12, and steam is mixed therewith by virtue of the steam connection to coil 12 from line 22 which extends from a source of steam at a higher pressure than that found in coil 12.

The mixture of oil and steam flows through coil 12, the steam giving up heat to the oil and condensing as it moves along. Steam from the above-mentioned source is, also, conducted into tank 10 through lines 26 which communicate with the interior of tank 10 when valves 28 are opened. The steam fills the space around coil 12 and serves to reheat the mixture inside the coil as it passes therethrough. Steam and air may return to the boiler as required through steam outlet line 30 connected to the uppermost portion of tank 10 when valve 32 is opened.

After the mixture passes through coil 12 and has been heated to a temperature approximately that of the steam surrounding the coil 12, line 18 connected to the coil 12 interiorly of the tank 10 conducts the hot mixture to an oil well or other point of usage as desired through the use of suitable equipment forming no part of this invention.

During the reheating of the fluid in the coil 12, condensation of steam will occur and gravitate to the bottom of tank 10. Steam trap 36 has been provided to allow the passage of water from the tank 10 to a receptacle from which it may be returned to the boiler. The trap 36, however, will not allow steam to escape from tank 10. The connecting line 38 from the lowermost part of tank 10 to the trap 36 has been disposed in such a manner that condensate will flow by gravity into the trap 36 and be discharged as it accumulates.

It is possible with the piping and valve arrangement provided to change the relative disposition of the oil and the steam in the heater structure. By closing the valve 16 in the normal inlet and opening valve 44 in line 42, oil flow will be diverted from the coil 12 into the tank 10, thereby filling the tank 10 with oil in surrounding relationship to coil 12. To keep the flow path, it is necessary to open valve 52 in line 50 at the bottom of tank 10 and thereby connect the tank 10 to outlet line 18.

With valve 24 in line 22 open, steam will be admitted to the coil and thereby heat the oil in the tank as the steam condenses. To dispose of the condensate which will accumulate in coil 12, it is required to connect the coil to steam trap 36, trap 36 having been previously isolated

from tank 10 by closing valve 40 in line 38. The opening of the valve 48 in line 46 will place coil 12 in communication with line 38 and steam trap 36.

It will be noted that valve 20 disposed between line 46 and line 50 will be closed to prevent the flow of oil into the steam trap 36. Steam may be introduced into the oil content of tank 10 by opening either or both of the valves 28 in lines 26. Valve 32 in line 30 may be used to prevent the flow of oil from tank 10 into the steam boiler if the oil pressure is higher than the steam supply pressure. Valve 32, therefore, would ordinarily be closed when oil is being introduced to the tank.

The introduction of steam into the oil as it enters the heating coil 12 is instrumental in increasing the efficiency of the heater and raising the outlet temperature of the oil to a maximum. As the steam enters the oil stream, violent turbulence results and its viscosity is immediately reduced. Both of these effects are beneficial to the transfer of the heat to the fluid because the thickness of the boundary layer at the tube wall is thereby reduced. Consequently, the overall heat-transfer co-efficient is increased, the result being absorption of the required heat in small, inexpensive equipment. It is obvious that the smaller equipment is more economical, not only as to initial cost of construction but required space in use and convenience of operation.

A further advantage of this novel device is the small volume of oil contained in the coil which makes for practically instantaneous results upon starting up. If such operation is desired, the oil to be heated would be introduced to the coil, and it would, therefore, be unnecessary to heat up a large volume of oil in the tank before the hot oil is obtained. Further, heavy tank construction would not be required if it is necessary to operate at high oil pressures. The wall thickness required by the tube coil 12 for high pressures would be small relative to that required for a tank designed to operate at the same pressures, thus presenting an overall economical structure.

The coil pattern as provided will allow freedom of movement that results from thermo-expansion and construction as variation of temperatures throughout the heater occur. Therefore, expansion joints are not required to accommodate the changes in length of the tube as it heats because of the inherent flexibility of the return bends.

The introduction of oil to tank 10 rather than coil 12 allows the storage of large quantities of heated oil, where such is required to furnish large flows for short periods. Therefore, the flexibility that is inherent in being able to change the oil from the coil to the interior of the tank surrounding the coil is of advantage to the extent of reducing the size of equipment required to perform the function of supplying the heated oil as required by the oil well treating equipment.

It is manifest, therefore, that many changes might well be made in details of construction, and those that fairly come within the broad aspect of this invention, as defined by the scope of the appended claim, are contemplated hereby.

Having thus described the invention, what is claimed as new and desired to be secured by Letters Patent is:

A treater comprising a hollow tank having a valved oil inlet pipe, a number of valved steam

inlet pipes, a valved steam outlet pipe and valved outlet means communicating with said tank; a continuous, tubular coil in the tank and having a valved inlet end extending through the tank adjacent the top thereof and a valved outlet end extending through the bottom of said tank; means for directing oil to be treated to said oil inlet pipe and to said inlet end of the coil; a valved steam inlet tube connected with said coil adjacent its inlet end; a steam trap; a valved conduit joining the tank at said bottom thereof with said steam trap; and a valved tubular member joining the coil adjacent its outlet end with said conduit.

ANDREW CRAIG RUSSELL.
